UNITED STATES PATENT OFFICE.

CARRIE J. LOOMIS, OF JOLIET, ILLINOIS.

SHOE.

SPECIFICATION forming part of Letters Patent No. 290,249, dated December 18, 1883.

Application filed October 2, 1883. (No model.)

To all whom it may concern:

Be it known that I, CARRIE J. LOOMIS, a citizen of the United States of America, residing at Joliet, in the county of Will and State of Illinois, have invented certain new and useful Improvements in Shoes for Burial Purposes, of which the following is a specification, reference being had therein to the accompanying drawings.

10 Figure 1 is a perspective view; Fig. 2, a cross-sectional view on line 2 of Fig. 1, looking toward the toe in the direction of the arrow, and Fig. 3 a cross sectional view of a portion of the sole.

15 This invention consists of a slipper or shoe for burial purposes, to be placed on the feet of deceased persons for burial.

Referring to the drawings, Fig. 1 represents the shoe complete, the sole *c* and sides *S* of which are designed to be made of felt material or its equivalent. The sides *S* are cut so they do not quite meet either at the heel or toe. The space between the sides, on the instep and extending down to the toe, is filled 25 with a flexible yielding worsted knit fabric, *D*, as is also the space at the heel between the sides, as is shown at *D'*. The upper edge of the shoe is provided with a flexible border, *B*, having a ribbon, *a*, for the purpose of shirring 30 the top of the shoe about the ankle and tying it in front in a knot, *a'*, as shown. The flexible material *D* *D'* is for the purpose of permitting the foot to swell without injury to the shoe. The flexible material *D* in front may be 35 substituted by a tongue, made of similar material to the sides, fastened to the inner side of the shoe at its toe, and having its sides or edges extend down on the inner sides to or near to the sole, as shown at *P* in Fig. 2. This 40 material and kind of tongue is intended to be used when the shoe is to be used for male per-

sons. The loose sides permit the same flexibility of the shoe as the material *D*.

The manner in which the sole is constructed is shown in Fig. 3. The two parts *c'* and *c''* 45 and the sides *S* are sewed together at the edge of the sole, as shown in said figure, and a stiffening, *F*, is placed between the two parts of the sole.

Any suitable material may be used for the 50 sides and the sole, but preferably felt material should be used for the two parts *c'* and *c''* of the sole, and also for the sides *S*, and paste-board for the stiffening *F* between the two parts of the sole. It is not intended that the 55 sole and sides should be as yielding or flexible as the other parts, or any more so than felt material would be.

When the tongue *P* is used, as described, a tie, *a'*, is used to tie over the instep, to hold the 60 sides up, as shown in Fig. 2.

The inner side of the shoe is designed to be quilted or lined with quilted material, as shown in Fig. 1. The shoe as illustrated, Fig. 1, thus forms a covering or dressing for the 65 feet of a deceased person, and is intended to be placed on permanently, to be interred with the person.

Having thus described my invention, what I claim as new, and desire to secure by Letters 70 Patent, is as follows, to wit:

The combination, with the sole consisting of the parts *c'*, *c''*, and *F*, of the sides *S*, independent from each other and formed of material less flexible than the parts connecting 75 them, the flexible front *D* and heel *D'*, flexible border *B*, and shirr-ribbon *a*, as and for the purpose set forth.

CARRIE J. LOOMIS.
